UNITED STATES PATENT OFFICE.

GIOVANNI VIRZI, OF NEW YORK, N. Y., ASSIGNOR OF ONE-HALF TO JOSEPH VIRZI, OF NEW YORK, N. Y.

FREE SOUNDING-BOARD.

1,349,700.

Specification of Letters Patent. Patented Aug. 17, 1920.

Application filed February 13, 1919. Serial No. 276,824.

To all whom it may concern:

Be it known that I, GIOVANNI VIRZI, a subject of the King of Italy, and a resident of the city of New York, borough of Manhattan, in the county and State of New York, have invented a new and Improved Free Sounding-Board, of which the following is a full, clear, and exact description.

The present invention relates to musical instruments and has for an object to provide an improved sounding board therefor.

In the accompanying drawings are shown illustrative embodiments of the invention.

Figure 1 is a longitudinal, central sectional view of a violin with a free sounding board constructed in accordance with the present invention;

Fig. 2 is a sectional view taken on the line 2—2, Fig. 1, looking in the direction of the arrow;

Fig. 3 is a sectional view taken on the line 3—3, Fig. 2;

Fig. 4 is a detail sectional view showing a connecting post and the manner of connecting the same to the main and auxiliary sounding boards;

Fig. 5 is a view of a free sounding board shown as applied to a grand piano;

Fig. 6 is a sectional view taken on the line 6—6, Fig. 5;

Fig. 7 is a sectional view taken on the line 7—7, Fig. 5, looking in the direction of the arrow; and

Fig. 8 is a detail sectional view taken on the line 8—8, Fig. 5.

The invention provides an auxiliary free sounding board for musical instruments which, together with the usual main sounding board, produces a more pleasing tone, as well as other advantages.

In the drawings, for the purposes of illustration of the invention, there is shown a violin equipped with a free sounding board constructed in accordance with this invention. The usual sounding board 1 is provided as heretofore and may be, as shown, reinforced by a central rib 2 which is found in the usual construction. The auxiliary sounding board 3 is spaced from the main sounding board and is approximately parallel thereto and sufficiently smaller to be free of the frame at the edges. The relative size

of the auxiliary board and the shape thereof may be varied within considerable limits, and it may be made flat or may conform to the shape of the principal sounding board, as desired. It is suitably connected to the main sounding board for support, as by spaced blocks or sound posts 5, but otherwise it is free from support by or contact with the frame or other parts of the instrument, to provide an auxiliary free sounding board.

The second construction is a sounding board designed for a grand piano. The main sounding board 7 may be, as shown, of usual construction reinforced by ribs 8, 9, 10, 11, 12, etc., which serve to stiffen the board as usual, and, also, in the construction shown serve to provide support for the auxiliary sounding board. These ribs are wide enough at certain spaced points to furnish supports 17, 18, 19, etc., for the auxiliary board which is rigidly attached thereto at these points, but therebetween the ribs are cut away, as indicated at 20, 21.

It is to be understood that the present invention may be applied to sounding boards of all kinds, especially to sounding boards for all sorts of stringed instruments. It is to be understood, further, that upon suitable occasions the free sounding board may be on the side of the main sounding board toward the strings, instead of upon the opposite side as indicated in the violin shown.

Having thus described my invention, I claim as new and desire to secure by Letters Patent:

1. In a musical instrument, the combination of a main sounding board, a plurality of ribs secured on one side of said board, said ribs being provided with integral projections, and an auxiliary sounding board secured upon said projections and held thereby in spaced relation to the main sounding board, all portions of the auxiliary sounding board being otherwise free from the main sounding board.

2. In a musical instrument, the combination of a main sounding board, an auxiliary sounding board, securing means between the main and the auxiliary sounding boards to hold the auxiliary sounding board in definite spaced relation to the main sounding

board, said securing means including a rib secured to one of said boards throughout its length, and having at least one integral extension to which the other sounding board is attached.

3. In a musical instrument, two closely adjacent and parallel sounding boards and

spaced ribs therebetween secured throughout their lengths to one sounding board but secured to the other sounding board only at 10 spaced points and cut away and spaced therefrom between such points.

GIOVANNI VIRZI.
